UNITED STATES PATENT OFFICE.

GEORGE S. SAVIGNAC AND CHARLES E. MYERS, OF ST. LOUIS, MISSOURI, ASSIGNEES,
BY MESNE ASSIGNMENTS, TO SIMPLEX SHOE MACHINERY COMPANY, OF ST. LOUIS,
MISSOURI, A CORPORATION OF MISSOURI.

SEAM FOR SEWED ARTICLES.

1,114,533.

Specification of Letters Patent.

Patented Oct. 20, 1914.

Application filed May 29, 1911. Serial No. 630,227.

To all whom it may concern:

Be it known that we, GEORGE S. SAVIGNAC and CHARLES E. MYERS, citizens of the United States, and residents of the city of 5 St. Louis and State of Missouri, have invented a new and useful Improvement in Seams for Sewed Articles, of which the following is a specification.

This invention relates to stitches for sewing leather and other heavy material of a similar nature.

It relates more particularly to loop-lock stitches, and has for its principal objects to produce a strong and durable stitch for 15 heavy work, such as shoe soles, harness, and the like; to produce a stitch which gives the required flexibility to the sewed material and permits of considerable wear without breaking the stitch; to produce a stitch 20 which is simple in formation and readily made by machinery; and to attain certain advantages hereinafter more fully appearing.

In stitching according to the ordinary 25 method of making a loop-lock-stitch the needle thread or stitching thread proper and the locking-loop thread are usually of the same kind and size. That is, the two threads comprise the same number of cords or 30 strands. The puncture in the material to be stitched is made straight and of substantially the same cross dimensions throughout; and the locking-loop is drawn by the needle loop into the puncture.

35 In sewing shoe soles the locking-loop thread is usually on the outside of the sole, and to permit of a certain amount of wear upon the sole before the stitches become worn and weakened the locking-loop thread 40 intermediate the loops is usually drawn into a groove provided therefor in the sole. After the sole is worn down and the groove is obliterated, the stitches soon become worn and broken; and, consequently, the layers of 45 the sole rip apart. So, too, in drawing the ordinary locking-loop-stitch tight, the flexibility of the stitched sole is impaired.

The present invention is designed to overcome the disadvantages above noted and it 50 consists in the features and arrangements and combinations hereinafter described and claimed.

In the accompanying drawing which forms part of the specification and wherein

like symbols refer to like parts wherever they occur,—Figure 1 is an enlarged section 55 through two layers of material showing the completed stitch and formation thereof according to our invention; Fig. 2 is a view similar to Fig. 1 showing the locking-loop 60 thread obliterated excepting the portions constituting the locking-loops; Fig. 3 is a fragmentary view showing a modification of the awl and puncture; and Fig. 4 is a similar view of a further modification of the 65 awl and puncture.

In producing a stitch according to our invention any ordinary loop-lock-stitch machine may be used, except that the awl or puncturing element must be provided with 70 an enlargement or tapering portion, so that the portion of the puncture in the work which receives the locking-loop is made considerably larger than the portion through which only the needle thread or stitching 75 thread proper passes. In practice, the awl may be round, square, or of any other angular cross section. It must have a puncturing portion 1, back of which is the enlargement or tapered portion 2.

In the drawings two layers of work A, B, 80 are shown. The puncture *a* in the layer A is straight while the puncture *b* in the layer B is outwardly flaring, being obviously formed by the awl C. The stitching thread proper 85 3 is passed through the eye of a needle D which carries the thread through the punctures in the layers A and B a sufficient distance to leave a loop 3^a beyond the outer face of the layer B.

The locking-loop thread 4 may be carried 90 in any desirable manner and laid through the needle thread loop 3^a. Usually the locking-loop thread 4 is looped around a reciprocating device adapted to lay the loop 4^a 95 through the needle thread loop 3^a and back away so that the take-up device may draw the needle thread and pull the two loops 3^a and 4^a interlocked into the puncture in the layer B.

In practice, the puncture *a* in layer A is 100 just large enough to permit the double thickness of the needle thread loop to be drawn therethrough, while the flared puncture *b* in the layer B is large enough at its outer end to readily receive the quadruple thickness of the locking-loop thread and double thickness of the needle thread loop. When

the needle thread is pulled by the take-up device the interlocked looped portions 3^a and 4^a of the two threads 3 and 4 are wedged in the flared opening. While it is obvious that the combined six thicknesses of thread forming the lock cannot be drawn into the smaller puncture α , yet, in some cases, it is preferable to use a heavier cord for the locking-loop than that which is used for the needle thread. For example, the needle thread may be a six cord thread and the locking-loop thread a twelve cord or twice as heavy as the needle thread. However, in other cases, the needle thread may be the heavier.

When the stitch is used for shoe soles the portions of the locking-loop thread between the punctures may be obliterated, thereby leaving only the wedged locking-loops embedded in the tapered punctures b . Hence, the shoe sole will be more flexible than if the tightly drawn portions of the locking-loop thread intermediate the locking-loops were not obliterated. So, too, the bottom layer B of the shoe sole may be worn nearly away and yet the remaining portion of the layer B will not rip apart from the layer A. Furthermore, it is not necessary to groove the bottom of the shoe sole as in the case of the ordinary loop-lock-stitch where protection must be made for the locking-loop thread to prevent it from being worn and cut.

In Figs. 3 and 4 modifications of the form of the awl and puncture in the work are shown. In the former, the awl is round in cross section and, instead of making the entire puncture tapered in the layer B of the work, only a portion is tapered; and in the latter figure, the awl is shown as being round in cross section and of two diameters with a rounded shoulder, so as to produce the counterpart puncture shown.

In practice, the locking-loop thread, and in some cases, both threads may be waxed in the usual manner; but we prefer to treat the threads with a liquid cementitious substance, which in hardening, makes a substantially solid wedge of the interlocked loops. In effect, the locking-loops thus treated, form substantially wedge-shaped or rivet heads, or pegs, so that the bottom of the shoe sole may be scraped and sandpapered and otherwise finished and polished; and the sole may be worn nearly away, as above set forth, and yet the layers hold together.

Another advantage in the present stitch over the ordinary stitch is that the leather is pressed so as to close tightly around the loops of the preceding stitches as the tapered or enlarged portion of the awl is forming the puncture for the succeeding stitch. Obviously, the shape of the puncture in the layer which receives the locking-loop may be varied without departing from our invention so long as the inner portion of the puncture is considerably smaller than the outer, so as to prevent the interlocked loops from pulling therethrough. Therefore, we do not wish to be limited to the specific form shown, nor do we wish to be limited to any particular machine for producing the stitch.

What we claim is:

1. Layers of leather or like material sewed together by looplocked stitches, the punctures therefor extending entirely through the work from top to bottom and flaring toward the lock side of the work, the successive flared portions being spaced apart, and the loop-locked portions of the thread being held squeezed in the flared portions of the punctures.

2. Layers of leather or like material sewed together by a continuous thread, looped successively through the work, the punctures therefor extending through the work from top to bottom, the flared portions being spaced apart, and lock-loops of thread inserted through the loops of said first mentioned thread, the interlocked portions of the threads being held squeezed in the enlargements of the respective punctures.

3. Layers of leather or like material sewed together by a continuous thread, looped successively through the work, the punctures therefor extending through the work from top to bottom, the flared portions being spaced apart, and lock-loops of heavier thread inserted through the loops of said first mentioned thread, the interlocked portions of the threads being held squeezed in the enlargements of the respective punctures.

Signed at St. Louis, Missouri, this 26th day of May, 1911.

GEORGE S. SAVIGNAC.
CHARLES E. MYERS.
